Inventor:
Leo J. Wahl

By: May W. Zabel Atty.

UNITED STATES PATENT OFFICE.

LEO J. WAHL, OF STERLING, ILLINOIS.

BLADE MOUNTING FOR CLIPPERS.

Application filed December 1, 1924. Serial No. 753,211.

To all whom it may concern:

Be it known that I, LEO J. WAHL, a citizen of the United States, residing at Sterling, in the county of Whiteside and State of Illinois, have invented a certain new and useful Improvement in Blade Mountings for Clippers, of which the following is a full, clear, concise, and exact description, reference being had to the accompanying drawings, forming a part of this specification.

My invention relates to hair clippers and more particularly to a blade mounting for clippers.

It is a purpose of my invention to provide a new and improved mounting for the movable blade of a hair clipper so as to reduce the friction in the connection between the means for reciprocating the blade and said blade so as to obtain a more easily operating device and a device that has a higher efficiency than has previously been the case.

My invention relates particularly to a blade mounting for electric clippers comprising a vibratory element that is vibrated by electro-magnetic means, said vibratory element being connected with the movable blade, my invention having for its purpose to provide a mounting for the clipper blade on the vibratory member so that there is a minimum of friction in the connection. This is quite important as the less friction there is in the movable parts of the device, the easier it is to properly tune the vibratory member.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a plan view partly broken away of a clipper showing my improved connection between the vibratory member and the movable clipper blade;

Fig. 2 is a fragmentary view partly in section and partly in elevation, said view being taken substantially on the line 2—2 of Fig. 1;

Fig. 3 is an end view of the device as viewed substantially from the plane 3—3 of Fig. 2; and

Fig. 4 is a section taken on the line 4—4 of Fig. 2.

Referring in detail to the drawings, my improved clipper comprises a casing 10 upon which is mounted the stationary or fixed blade 11 at one end thereof. Mounted within the casing is an electro-magnet having the coil 12 with which the armature 13 cooperates, the coil 12 vibrating said armature due to the provision of the spring member 14 on the end thereof which is secured to the casing by the securing member 15.

The vibratory member 13 has a transversely extending end portion 16 to which is secured an angular bracket 17, said bracket being secured by any suitable securing means such as the screws 18. Mounted to reciprocate transversely of the blade 11 is the movable blade 19 upon which is mounted a block 20 which is secured to the member 19 by means of any suitable securing device such as the screws 21.

Mounted on said block and secured in position by said screws are the spring clips 22 which are provided with end portions 23 bent around the ends of the block 20 and with upstanding ends 24 that are bent back on themselves as at 25 to provide a depending finger portion 26, thus providing in effect a double spring portion on each of the members 22. The portions 26 are slightly spaced and the end portion 27 of the bracket 17 extends between the same. Said end portion 27 is cut away to form a reduced finger portion 28 extending from the top edge thereof outwardly beyond the body portion of the member 17. The portion 28 is substantially square in cross section as will be clear from Fig. 4 and operates in a slot 29 in the block 20, the block 20 being slightly widened as at 30 to provide sufficient material on all sides of the slot 29. The forward edge of the member 27 below

the finger 28 is cut away so as to incline slightly toward the rear of the bracket as will be clear from Fig. 2, said cut away portion being indicated by the numeral 31 and 5 being provided to space the forward end 27 of the member 17 from the block 20.

By providing the finger 28 operating in the slot 29, the friction between the springs 26 and the member 17 is reduced to a minimum. In operation, as the blade 19 reciprocates, it is tending to travel in a slightly arcuate path substantially about a center where the member 14 is secured to the casing by means of the securing means 15. Also 15 due to the distance between the blades, the blade 19 substantially engages flatly with the blade 11. This causes a tilting of the member 17 relative to the blade to the right and left of the position shown in Fig. 3 20 against the tension of the springs 26. This movement is allowed for by means of the slot 29.

Furthermore, due to the fact that the blade 19 engages flatly against the blade 11 as the 25 blade travels to the opposite ends of its movement in its reciprocation, the member 17 tilts substantially about the end of the finger 28 relative to the block 20 and it is this tilting motion that causes friction between the spring members 26 and the end 30 of the blade 27. By provision of the finger 28 adjacent one edge of the member 17, the lever arm of this movement is made as small as is possible without affecting the flexibility 35 of the mounting of the blade 19. Thus the effect of the friction of the springs 26 against the sides of the member 17 is reduced as much as is possible without detracting anything from the flexible mounting of the 40 blade.

Having thus described my invention, what I desire to claim and secure by United States Letters Patent is:

1. In a clipper, a stationary blade, a blade 45 movable transversely of said stationary blade, means for reciprocating said movable blade comprising a connection having a single finger thereon and a member mounted to move with said movable blade having an opening therein with which said finger engages.

2. In a clipper, a stationary blade, a blade 55 movable transversely of said stationary blade, means for reciprocating said movable blade comprising a connection having a finger thereon and a member mounted to move with said movable blade having an opening therein with which said finger engages, said member having a pair of clips engaging with 60 opposite sides of said connection.

3. In a clipper, a stationary blade, a blade 65 movable transversely of said stationary blade, means for reciprocating said movable blade comprising a connection having a finger thereon and a member mounted to move

with said movable blade having an opening therein with which said finger engages, said member having a pair of clips engaging with opposite sides of said connection, said connection being otherwise free of said member. 70

4. In a clipper, a stationary blade, a blade movable transversely of said stationary blade, means for reciprocating said movable blade comprising a connection having a single finger thereon and a member mounted to 75 move with said movable blade having a slot extending in the direction of movement thereof therein with which said finger engages.

5. In a clipper, a stationary blade, a blade 80 movable transversely of said stationary blade, means for reciprocating said movable blade comprising a connection having a single finger thereon and a member mounted to move with said movable blade having an opening therein with which said finger engages, said member having a pair of resilient clips engaging with opposite sides of said connection. 85

6. In a clipper, a stationary blade, a movable blade, a block mounted on said movable blade having an opening therein, a pair of clips on said block, means for reciprocating said blade comprising a member engaging between said clips and a finger on said member 90 engaging in said opening. 95

7. In a clipper, a stationary blade, a movable blade, a block mounted on said movable blade having a slot therein, a pair of clips on said block, means for reciprocating said blade comprising a member engaging between said clips and a finger on said member 100 engaging in said slot. 105

8. In a clipper, a stationary blade, a movable blade, a block mounted on said movable blade having an opening therein, a pair of clips on said block, means for reciprocating said blade comprising a member engaging between said clips and a finger on said member adjacent one edge thereof engaging in 110 said opening. 115

9. In a clipper, a stationary blade, a movable blade, a block mounted on said movable blade having an opening therein, a pair of clips on said block, means for reciprocating said blade comprising a member engaging between said clips and a finger on said member at the extreme outer end thereof engaging in 115 said opening. 120

10. In a clipper, a stationary blade, a movable blade, a block mounted on said movable blade having an opening therein, a pair of clips on said block, means for reciprocating said blade comprising a member engaging between said clips and a finger on said member adjacent one edge thereof engaging in 125 said opening, said member being cut away to provide clearance between said member and said block. 125

11. In a clipper, a stationary blade, a mov-

able blade, a block mounted on said movable blade having an opening therein, a pair of clips on said block, means for reciprocating said blade comprising a member engaging between said clips and a finger on said member at the extreme outer end thereof engaging in said opening, said member being cut

away to provide clearance between said member and said block.

In witness whereof, I hereunto subscribe my name this sixth day of November, A. D. 1924.

LEO J. WAHL.
